UNITED STATES PATENT OFFICE.

FREDERICK M. BENNETT, OF NEW YORK, N. Y.

ELECTRICAL MEASURING INSTRUMENT.

SPECIFICATION forming part of Letters Patent No. 642,563, dated January 30, 1900.

Application filed April 29, 1898. Renewed July 3, 1899. Serial No. 722,695. (No model.)

To all whom it may concern:

Be it known that I, FREDERICK M. BENNETT, a citizen of the United States, and a resident of New York, in the county and State 5 of New York, have invented a certain new and useful Electrical Measuring Instrument, of which the following is a specification.

My invention relates to indicators or current-measuring devices for electrical instruments; and it has for its object the provision of an organization of the class described simple in construction, inexpensive to manufacture, and efficient in practical use.

To attain the desired end, this my invention consists in the construction, arrangement, and operation of parts herein set forth.

In the drawings which accompany and form a part of this specification, Figure 1 represents a front elevation of my meter; Fig. 2, 20 a top or plan view with the cover removed; and Figs. 3, 4, 5, 6, and 7 are views in detail of my indication-needle and support therefor.

Like letters of reference indicate like parts in all the views.

25 I have found it desirable to make a portable electrical instrument of simple construction and which may be either utilized primarily as an ammeter or a voltmeter and also for other purposes as a galvanometer, and I 30 have therefore constructed according to my invention an organization of the class described embodying the preferred construction of parts and their mutual relationship, combination, arrangement, and organization 35 in a composite body or structure, as herein-after described.

Referring particularly to the drawings, A denotes my armature, consisting of an excitable metallic material, preferably a pivoted 40 metallic bar, as a plate of soft iron or a permanent bar-magnet, and either solid or laminated, or consisting of a mass or coil of wire, and constructed and arranged to be deflected by the passage of an electric current through 45 a coil located adjacent to the same and provided with preferably vertical needle points or pivots A², preferably connected by a bridge A'. My armature A is also provided with a relatively obliquely inclined index-finger A³, 50 terminating in an indicating-point A⁴. The needle-points A² ordinarily rest or are loosely set in suitable centers d³, formed in pieces of plumbago, or in jewels D², placed in the frame or bobbin D, containing means for setting up

a magnetic field, as a hollow coil C. The top 55 of my preferably horizontal frame D is ordinarily slotted, as at D', for the insertion therein of the armature, and it also usually supports a guard B to prevent the displacement of said armature when the instrument is inverted. The coil C is provided with terminal binding-posts of ordinary construction, and my instrument also has a scale of practically the same design as those heretofore used, which scale is curved in order to register with 60 the path of movement of the index-point A⁴.

It is manifest that various omissions of some particulars could be made without materially affecting the essential features of my invention or the operation of the remaining parts, 70 and I do not therefore wish to be limited to the specific structural details of the organization herein set forth. Obviously the elements of the structure described may be located at an angle to the plane in which they 75 are shown. I accordingly use the words "horizontal," "vertical," and the like in a relative sense.

In practical use the top cover is removed and the armature-pivots are set in plumbago 80 or other centers, whereupon the index will point to zero.

By lengthening the ends or needle pivot-points the instrument becomes more sensitive, the said points being below the center 85 of gravity, and the obliquely-disposed finger (which may be adjusted by bending the same more or less to one side) acts as a balance for the excitable metal material, as the plate or armature, and my instrument is rendered 90 more sensitive by reason of the fact that the needle-points and index-finger are obliquely inclined preferably at practically the same angle. It will be observed that the mass of metallic material is set above the coil and is 95 provided with bearing-pivots projecting downward and having eccentrically-located pivots, so that the points of the excitable material will work respectively in and out of said coil, whereby a rocking and eccentric motion of 100 the excitable material is produced.

In Figs. 6 and 7 my excitable material consists of a disk and has a rolling motion down into the coil, the spindle of my needle-points being placed a little out of the center of the 105 plate in order that the longer end of the same may tend to balance the said index-finger.

I prefer to make my bobbin D of material

having a vitreous surface, as glazed porcelain, in which case the centers D³ will be formed in the said bobbin by glazed recesses, the vitreous faces of which thus obviate the 5 necessity of using the jewels D².

As it is evident that many changes in the construction and relative arrangement of parts might be resorted to without departing from the spirit and scope of my invention, I 10 would have it understood that I do not restrict myself to the particular construction and arrangement of parts shown and described, but that such changes and equivalents may be substituted therefor, and that 15

15 What I claim as my invention is—

1. In combination, a coil, an excitable metallic material set above the coil, and provided with bearings projecting downward and having eccentrically-located pivots so that 20 the outer portions of the excitable material will work respectively in and out of said coil, the said excitable material being provided with an index-finger, whereby a rocking and eccentric motion of the excitable material is 25 produced.

2. In combination, a coil, an excitable metallic material set above the coil, and provided with bearings projecting downward and having eccentrically-located pivots so that 30 the outer portions of the excitable material will work respectively in and out of said coil, the said excitable material being provided with an obliquely-inclined index-finger, whereby a rocking and eccentric motion of the excitable material is 35 produced.

3. In combination, a coil, an excitable metallic material set above the coil, and provided with bearings projecting downward and having eccentrically-located pivots so that 40 the outer portions of the excitable material will work respectively in and out of said coil, the said excitable material being provided with an index-finger, whereby a rocking and eccentric motion of the excitable material is 45 produced, and a guard to prevent the said excitable material from being removed from the coil.

4. In combination, a coil, an excitable metallic material provided with inclined needle 50 points or pivots, so that the outer portions of the excitable material will work respectively in and out of said coil, the said excitable material being provided with an index-finger.

5. In combination, a coil, an excitable metallic material provided with inclined needle points or pivots, so that the outer portions of the metallic material will work respectively in and out of said coil the said metallic material being provided with an obliquely-inclined index-finger.

6. In combination, a coil, an excitable metallic material provided with inclined needle points or pivots, so that the outer portions of the metallic material will work respectively 65 in and out of said coil the said metallic material being provided with an inclined index-

finger, the incline of the needle-points and index-finger being at practically the same angle.

7. A bobbin having a vitreous surface and 70 provided with recesses also having vitreous faces, in combination with a pivoted metallic material provided with bearing-points to engage the said recesses.

8. A bobbin having a vitreous surface and 75 provided with recesses also having vitreous faces.

9. In combination, means for setting up a magnetic field, an excitable metallic material provided with bearings projecting downward 80 and having eccentrically-located pivots, supports for the same, the whole so constructed and arranged that the outer portions of the excitable material will work in and out of said magnetic field, whereby a rocking and 85 eccentric motion of the excitable material is produced.

10. In combination, means for setting up a magnetic field, an excitable metallic material provided with bearings projecting downward 90 and having eccentrically-located pivots, supports for the same, the said excitable material being provided with an index-finger, the whole so constructed and arranged that the outer portions of the excitable material will 95 work in and out of said magnetic field, whereby a rocking and eccentric motion of the excitable material is produced.

11. In combination, means for setting up a magnetic field, an excitable metallic material provided with bearings projecting downward 100 and having eccentrically-located pivots, supports for the same, the said excitable material being provided with an obliquely-inclined index-finger, the whole so constructed and arranged that the outer portions of the excitable material will work in and out of said magnetic field, whereby a rocking and eccentric motion of the excitable material is 105 produced.

12. In combination, means for setting up a magnetic field, an excitable metallic material provided with bearings projecting downward 110 and having eccentrically-located pivots, supports for the same, the said excitable material being provided with an index-finger, the whole so constructed and arranged that the outer portions of the excitable material will work in and out of said magnetic field, whereby a rocking and eccentric motion of the excitable material is 115 produced, and a guard to prevent the said excitable material from being removed.

In testimony of the foregoing specification I do hereby sign the same in the city of New 120 York, county and State of New York, this 3d day of December, A. D. 1897.

FREDERICK M. BENNETT.
